UNITED STATES PATENT OFFICE.

WALTER J. DUFFEY, OF FORT WILLIAM, ONTARIO, CANADA.

CAR LOADER.

Application filed September 2, 1921. Serial No. 498,150.

To all whom it may concern:

Be it known that I, WALTER J. DUFFEY, a subject of the King of Great Britain, and resident of the city of Fort William, Province of Ontario, in the Dominion of Canada, have invented certain new and useful Improvements in Car Loaders, described in the following specification and illustrated in the accompanying drawings, that form part of 10 the same.

The principal objects of the invention are, to effect a saving of time and expense in the loading of box cars, and to devise a construction of loader which will be very simple to operate but strong and durable in construction.

The principal features of the invention consist in the novel construction and arrangement of parts, whereby a pair of endless carriers supported upon a movable carriage are operated to carry the material being loaded to the ends of the car, and whereby the carriers are manipulated and controlled.

25 In the drawings, Figure 1 is a side elevational view of my improved carrier shown in the loading position projected into a box car.

Figure 2 is a plan view.

30 Figure 3 is a front end elevational view showing the carrier extended.

In the loading of box cars with coal, stone and like material it is desirable that the load be uniformly distributed and this 35 cannot be done with the ordinary chute.

In the present invention the loader which is formed of a pair of endless carriers adapted to extend toward each end of the car is supported upon a frame 1, here shown 40 formed of a pair of I beams rigidly connected together by cross plates 3 extending across the tops thereof. These I beams are supported upon a plurality of rollers 4 arranged upon shafts 5 supported in brackets 6 carried on a suitable foundation 7 which is arranged adjacent to the trackway upon which cars to be loaded are run.

50 A series of rollers 8 are arranged in the brackets 6 to engage the upper surface of the bottom flange of the I beams to hold the frame down to the rollers and to ensure its retaining a horizontal position.

Between the I beams 2 and rigidly secured to the foundation are a series of brackets 9 55 supporting the toothed rack 10 and the shaft 11 mounted in suitable bearings on the

frame 1 and extending transversely thereof carries a gear wheel 12 which meshes with the bracket 10.

On the shaft 11 is also mounted a worm 60 wheel 13 which is operated by a worm 14. The worm 14 is carried on a sleeve controlled by a friction clutch 15 which is mounted upon the shaft 16 driven by the motor 17.

65 A pair of fabricated frames 18 are supported on the end of the frame 1 projecting from the supporting rollers and between these frames are journaled a pair of shafts 19 arranged adjacent to the bottom and upon each of these shafts are pivotally supported a pair of metal plates 20 which form the sides of the conveyors.

70 Shafts 21 extend between the outer ends of each pair of the plates 20 and upon the shafts 19 and 21 are mounted suitable sprockets. These sprockets carry the endless carriers 22.

75 Cross bars 23 are arranged between the plates 20 adjacent to the outer shafts and also at the inward ends, the inner ones not being shown and between these cross bars and side plates are supported metal platforms 24 to support the laden carriers.

80 On the shafts 19 are mounted a pair of inter-meshing spur gears 25, one of which is driven by a pinion 26. The pinion 26 is driven by a spur gear 28 carried on a shaft 27 mounted in suitable bearings, and said gear 28 in turn is driven by a pinion 29 connected with a friction clutch 30 mounted on the shaft 16. Through this connection the motor operates the gears 25 to operate the endless carriers to move outwardly from the centre and to carry material deposited thereon at the ends of said conveyors.

85 A pair of shafts 31 and 32 are mounted in the upper part of the frames 18 vertically the one above the other and are operatively connected with the spur gears 33 and 34. The lower shaft is operated by a chain 35 which extends downwardly around a sprocket carried on the shaft 36 and connected by a clutch 37 to a spur gear 38 mounted on said shaft and operated by a pinion 39 carried on one of the shafts 19.

100 The upper shaft 31 is provided with a pair of cable drums 40 and pairs of cables 41 and 42 are mounted upon said drums and extend outwardly to the outer ends of the pivotal carrier frames. The rotation of the upper shaft 31 causes the raising of the

carrier shafts and in order to maintain the carrier frames in the desired position a ratchet wheel 43 is secured on the shaft 31 and said ratchet is engaged by a dog 44. 5 This dog is operated by a rod 45 extending horizontally to a point adjacent to the motor and is provided with a cam adapted to lift the ratchet dog.

- 10 A sleeve 46 is mounted on the rod 45 and to this sleeve is connected a crank arm 47 to which is connected a link 48 operatively connected with a clutch member 37 so that said clutch may be utilized as a brake when the dog holding the cable drums is released. 15 A lever 49 is arranged adjacent to the operator and connected with a clutch operating member 50 controlling the friction clutches 15 and 30.

In the operation of this device the car 20 to be loaded is placed opposite to the loader, the frame 1 of which is drawn back clear of the trackway. When the door is opposite to the frame 1 the operator throws in the clutch 15 to operate the worm which 25 rotates the spur gear causing it to travel over the rack 10 and carrying the frame 1 outwardly so that the outer end is extended into the centre of the car. The carriers are of course in the raised position 30 shown in dotted lines in Figure 3 to pass through the door way and when they have 35 passed inside, the operator releases the dog and lowers said carriers by manipulating the brake. The loading chute 51 is then 40 introduced through the opposite door of the car and the material to be loaded into the car is borne on to the carriers which are operated by the manipulation of the clutch 15 to drive said carriers.

- 45 An inverted V-shaped guard 52 is placed over the junction of the two carriers so as to prevent the material from piling and jamming in between. The carrier may be manipulated to move transversely of the car during the loading operation so that every portion will be properly loaded and as the piles of material at the ends of the car rise the carriers may be lifted by manipulating the lifting cables through the clutch 50 37. When the car has been completely loaded the clutch 37 is operated to pull the carriers into the raised position and the frame 1 is then operated to withdraw the loader from the car. 55 A car loader such as described may be manipulated with ease from one position to another and is very easily controlled.

What I claim as my invention is:—

1. In a car loader, the combination with 60 a movable carriage, a pair of upright frames at the outer end, a pair of shafts extending across said frames, intermeshing gears se-

cured to said shafts, frames mounted on said shafts and adapted to extend outwardly, endless carriers carried in said frames operated from said shafts, a shaft extending across the top of said end frame, cable drums on said top shaft, cables secured to the outer ends of said pivotal frames and connected to said drums, means for rotating said drum shaft, a clutch controlling the operation of said drum shaft, and ratchet means for holding said drum shaft to retain said carrier frames in various inclined positions. 75

2. A car loader, comprising, a rigid foundation, a plurality of horizontal roller supports carried on said foundation, a frame formed of channel sections supported on said rollers, rollers engaging the upper sides of the flanges of said sections to retain the frame in a horizontal position, a toothed rack supported on said foundation, a shaft transversely journaled on said frame, a spur gear on said shaft meshing with said rack, a worm gear operating said shaft, a clutch controlling the operation of said worm gear and a pair of endless carriers pivotally supported at the outer end of said frame and adapted to extend within the car. 80

3. In a car loader, a horizontal movable carriage a pair of endless carriers mounted at the end of said carriage and extending outwardly therefrom, a train of gears driving said endless carriers, a clutch controlling said train of gears, a fixed rack arranged on the foundation of the carriage, a spur gear mounted on the carriage meshing with the rack, a worm gear operating said spur gear, a clutch controlling said worm gear, means for controlling said clutches from the carriage, and means for controlling said pivotal carriers operated from the carriage. 90

4. In a car loader, a horizontal movable frame having rigid uprights at its upper end, a shaft extending across the top of said uprights, a sprocket wheel mounted on said shaft, a spur gear journaled in one of said rigid uprights, a clutch connected with said spur gear, a sprocket wheel operated by said clutch, a chain connecting said sprocket wheels, means for operating said clutch, means for rotating said spur gear, a pair of endless conveyers pivotally supported from said rigid uprights, a pair of cable drums operatively connected with the transverse shaft at the top of said uprights, cables connecting said drums with the outer end of said carriers, and means for holding the cable drums in adjusted positions. 100

WALTER J. DUFFEY.
